APPARATUS FOR PRESSING THE BOTTOM HEEL REGION OF A LASTED UPPER

Thomas Dell, Brooklyn, N.Y., assignor of fifty percent to Palizzio, Inc., New York, N.Y., a corporation of New York

Filed June 8, 1959, Ser. No. 818,663

6 Claims. (Cl. 12—53.5)

This invention relates generally to shoe manufacturing equipment, and is especially concerned with apparatus for pressing the nether heel region of a lasted shoe upper.

As is well known, the underside of the shoe upper in the heel region is necessarily pressed flat to eliminate wrinkles and folds, so that a clean juncture results between the heel and upper. This pressing operation has heretofore been one requiring considerable effort and manual skill, and consequently resulting in an excessive percentage of rejects.

Accordingly, it is one object of the present invention to provide apparatus for pressing the nether heel region of a lasted shoe upper which eliminates the need for skilled labor, minimizes the operator's effort, and which produces a consistently superior pressing operation, to substantially eliminate rejects.

It is a further object of the present invention to provide apparatus of the type described wherein it is merely necessary for an operator to load a lasted shoe upper and push the latter to a pressing station, where the pressing operation is automatically performed and the pressed article is returned to the loading station for unloading by the operator. Thus, the instant invention is admirably well suited for automatic loading and unloading, so as to be completely automatic without the need for skilled operating personnel.

It is a further object of the present invention to provide apparatus having the advantageous characteristics mentioned in the preceding paragraphs, which is extremely simple in structure, entirely reliable in operation, and which is durable and economical in use. In particular, the apparatus of the instant invention is capable of being manufactured, installed and operated relatively inexpensively, and to effect considerable savings in labor and the reduction or elimination of rejects.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

Fig. 1 is a side elevational view showing apparatus of the present invention with a lasted shoe upper in the loading position;

Fig. 2 is a partial side elevational view similar to Fig. 1, but illustrating the pressing operation;

Fig. 3 is a horizontal sectional view taken substantially along the line 3—3 of Fig. 1, but with the lasted shoe upper removed and illustrated in phantom in both its loading and pressing position;

Fig. 4 is a partial front elevational view, taken in the

2

direction of the arrow 4 in Figure 1, and partly broken away for clarity of understanding; and

Fig. 5 is a schematic representation of electrical and fluid circuitry associated with the instant apparatus.

Referring now more particularly to the drawings, and specifically to Fig. 1 thereof, a base or platform is there designated 10, and a post or standard 11 is fixedly secured to the base and extends upward therefrom spaced from the front end of the base (the right hand end as seen in Fig. 1). Carrier means, generally designated 13, is mounted on the upper side of the base 10, at the front region thereof, for carrying a lasted shoe upper, generally designated 14 between loading and pressing stations. Carried by the post 11, spaced above the base 10 and over the carrier 13 is pressing means, generally designated 15.

The carrier means 13 includes a generally forwardly and rearwardly extending bed plate or guide 17 disposed horizontally on the upper surface of the base and fixedly secured thereto, as by fasteners 18 (see Fig. 3) with its forward end projecting forward beyond the base. The bed plate or guide 17 is formed in its upper side with a longitudinally extending, upwardly facing slot or groove 19 which opens forwardly through the forward end of the bed plate and opens rearwardly into a laterally extending, open ended groove 20. The groove 19 provides a longitudinal guide or slide way, and may be defined between a pair of generally forwardly and rearwardly extending, parallel spaced bars 21 secured to the upper surface of the bed plate 17. At the rearward end of the bed plate 17 is provided an upstanding, laterally extending end wall 22 which combines with the rearward ends of the plates 21 to define the laterally extending groove 20. A stop member or abutment plate 23 may be fixed to the forward end of the bed plate 17, as by fasteners 24, and is arranged to extend laterally across the forward end of the slot 19 and vertically upward beyond the upper sides of the bars 21.

The carrier means 13 further includes a slide or carrier proper 27 slidably located in the guideway or slot 19 for reciprocatory movement therealong, and extending vertically above the upper surfaces of the side bars 21. As seen in Fig. 3, it will be noted that the facing sides of the bars 21 are undercut, as at 28, while the slide or carrier proper 27 is provided with flanges 29 engageable in the undercuts 28. Thus the slide 27 is freely slidable in the slot 19 without being removable therefrom. Of course, the slide 27 may be removed, if desired, by prior removal of the abutment plate 23.

An upstanding retaining pin or lug 30 is provided on the upper surface of the slide 27 for removably retaining a lasted shoe upper in position on the slide. That is, the last 31, see Fig. 1, is conventionally provided with a hole or bore 32 extending downward or inward through its upper surface in the rearward region of the last. With the last inverted, the pin 30 is freely engageable in the hole 32 when the last is seated on the upper surface of the slide 27 to retain the last in position on the slide. While observing the lasted shoe upper 14, it will be noted that the upper proper is designated 33 and has its nether heel portion 34 turned over to the underside of the last 31, and there secured in position in the conventional manner. Of course, as the last 31 is inverted, the underside 34 of the upper heel portion is uppermost in the drawings.

Resilient means, say in the form of a coiled compression spring 37 is interposed between the rearward end of slide 27 and the rear upstanding wall 22, having its opposite ends respectively secured thereto, to resiliently urge the slide toward its forward or loading station, as seen in Figs. 1 and 3. Thus, the slide 27 is resiliently urged for

ward, and is necessarily manually or otherwise shifted rearward against the force of resilient means 37. Obviously, upon release of the slide 27 from its rearward position or pressing station, that illustrated in Fig. 2, the spring 37 forcibly shifts the slide forward into abutting engagement with the abutment or stop member 23. Sharp impact of the slide moving forwardly against the abutment member 23 is likely to cause inertial movement or jumping of the lasted shoe upper 14 from its receiving engagement with the pin 30. Hence, means are provided in the form of a resilient leaf spring or retarder 38 to more gradually retard forward movement of the slide 27. The leaf spring 38 may be anchored to one bar 21, as by a fastener 39, and extend therefrom over the slot 19 in the forward region thereof into the path of forward movement of the slide 27. The slide 27, in its forward movement, engages with the retarding element 38 to deflect the latter to the condition illustrated in Fig. 3, and is frictionally engaged by the latter so that its forward motion is smoothly retarded.

Fixed to the bed plate 17 at the rearward region thereof, as by a bracket 41 is a limit switch 42 having a deflectable arm 43 extending into position over the bed plate 17 rearward of the slot 19. The arm 43 may have its free end resiliently deflectable in a horizontal direction, and is engageable with a button 44 to operate the switch 42. A headed projection 45 extends rearward from the rear end of the slide 27, being carried by the latter, and is engageable upon rearward movement of the slide with the switch arm 43 to operate the switch 42. Stated otherwise, the switch 42 is operated by engagement of the headed member 45 with the switch arm 43 upon movement of the slide 27 to the pressing station. If desired, the headed member 45 may be adjustable to project rearward beyond the slide 27 a desired distance, say by a threaded connection of the latter.

Carried by the post 11 for engagement with the lasted shoe upper 14 to limit movement of the latter into its pressing station is stop means, generally designated 48, which includes an annulus or collar 49 slidably circumposed about the post 11 for adjustment relative thereto and adapted to be fixed in any desired position by a set screw 50. Extending radially outward from the collar 49 is a shank 51, from which extend a pair of outwardly divergent arms 52, the arms being preferably covered with suitably resiliently yieldable material, such as foam rubber or the like. The shank 51 may be adjustable relative to the collar 49 radially inward and outward thereof; and, the stop means 48 is normally positioned with the shank 51 extending forwardly, and the arms 52 extending forwardly and diverging from each other in position to receive therebetween the heel region of the lasted shoe upper to limit rearward movement of the latter to the pressing station.

The pressing means 15 is constituted of a generally vertically disposed cylinder 55 fixedly secured to a sleeve 56 slidably circumposed about the post 11 and provided with set screws 57 for adjustably fixing the sleeve and cylinder at a desired elevation directly over the pressing station. Interiorly of the cylinder is provided a piston 58, see Fig. 5; and, fluid conduit means 59 is connected to the cylinder for communication with a source of fluid under pressure. Spring means 60 may be provided interiorly of the cylinder 55, for urging the piston upward. A plunger or rod 61 depends vertically from the piston 58 through the lower end of the cylinder 55 for vertical reciprocation with the piston. On the lower, external end of the plunger 61 is carried a pressing head, generally designated 62, which performs the pressing operation on the shoe upper region 34.

The pressing head 62 includes a mounting member or block 63 fixed to the lower end of the plunger or rod 61 for vertical movement therewith toward and away from the pressing station of the slide 27. A guide plate 64 may be adjustably fixed to the post 11, extending generally horizontally forward therefrom, and provided with a through opening 65 slidably receiving and guiding vertical movement of the mounting block 63. This is best seen in Fig.

4. It will also be there observed that the mounting block 63 is provided on its underside with a downwardly facing recess or bore 66 in substantial alignment with the plunger 61, and an additional, smaller downwardly facing recess 67 spaced from the bore 66.

A generally flat pressing plate 70 is located in spaced relation below the mounting block 63 and provided on its upper surface with a rearwardly facing channel member or carrier 71. That is, the carrier 71 is generally an open-ended rearwardly facing channel with the pressing plate 70 fixedly secured to the underside of the channel. A relatively heavy or stiff coil spring 73 is disposed generally vertically within the recess 66 of the mounting block 63, having its upper end secured by any suitable means to the mounting block, and depends below the lower surface of the mounting block to have its lower end connected by a fastener 76 to the upper region of the carrier. Thus, the pressing plate 70 and its carrier 71 are mounted for vertical movement relative to the mounting plate 63 and 20 slight angular tilting or canting relative to the mounting block by means of the spring 73. To limit this movement of the pressing plate 70 and its carrier 71 relative to the mounting block 63, a pin or lug 74 projects upward from the upper side of the carrier into spaced inter-engagement 25 within the downwardly opening mounting block hole 67.

If desired, a heating assembly 75 may be secured within the channel-shaped carrier 71, the heating assembly including a heating element 75a extending substantially through the carrier to transmit heat to the presser plate 70. The heating assembly 75 may be electrically energized, as 30 through conductors 77.

In Fig. 5 is shown in schematic representation wherein an electrically operated valve 78, say a solenoid valve, is interposed within the fluid conduit means 59 between the 35 fluid pressure source and cylinder 55. An electric circuit, including a timer 79 is connected by conductors 80 to the valve 78, and a supply line 81 to a source of electrical supply. The switch 42 is connected by conductors 43 to the timer 79.

In operation, an operator places a lasted shoe upper 14 in inverted condition on the slide 27 at its loading position, the condition of Fig. 1. The lasted shoe upper 14 is pushed rearward into limiting engagement with the stop arms 52 at the pressing station. In this condition, as illustrated in Fig. 2, the coil spring 37 is compressed, 45 and the switch arm 43 swung rearward to close the switch 42 which operates the valve 78 for a predetermined time interval, as controlled by the timer 79. Operation of the valve 78 initially admits fluid under pressure to the cylinder 55 to shift the piston 58, and the pressing head 62 downward into pressing engagement with the nether heel portion 34, as illustrated in Fig. 2. The pressing plate 70 will conformably engage with the lasted shoe upper, and simultaneously press and heat the latter to accomplish the desired permanently pressed condition. At the 50 elapse of the predetermined time interval, fluid will be released from the cylinder 55, permitting the spring 60 to return the piston 58 upward and lift the pressing head from its pressing engagement with the lasted shoe upper. This releases the spring biased slide 27 for forward movement under the force of spring 37 to its loading position, as in Fig. 3, for removal and replacement of the last shoe upper. It will now be appreciated that operation of the 55 pressing means 15 is actuated by closing of the switch 42 which energizes the electrical circuit of the valve 78 to operate the pressing means.

From the foregoing, it is seen that a device for pressing the bottom heel region of a lasted shoe upper is provided which fully accomplishes its intended objects and 60 is well adapted to meet practical conditions of manufacture and use.

Although the present invention has been described in some detail by way of illustration and example for purposes of clarity of understanding, it is understood that 65 certain changes and modifications may be made within

the spirit of the invention and scope of the appended claims.

What is claimed is:

1. Apparatus for pressing the bottom heel region of a lasted shoe upper, said apparatus comprising a carrier for the lasted shoe upper mounted for reciprocatory movement between a loading station and a pressing station, pressing means movable toward and away from said pressing station into and out of pressing engagement with a lasted shoe upper at said pressing station, and actuating means responsive to movement of said carrier to said pressing station for actuating said pressing means, said pressing means comprising a mounting member movable toward and away from said pressing station, a pressing member interposed between said mounting member and said pressing station, and mounting means mounting said pressing member for movement with said mounting member and for resiliently yieldable universal movement relative to said mounting member for conforming pressing engagement with the lasted shoe upper.

2. Apparatus according to claim 1, said mounting means includes a stiff coil spring having its opposite ends fixedly secured to said mounting member and said pressing member respectively, and rigid guide means on said mounting and pressing members in loosely interfitting relation with each other to constrain said pressing member to movement relative to said mounting member generally toward and away from the latter and to limited angular movement relative to said mounting member.

3. Apparatus for pressing the bottom heel region of a lasted shoe upper, said apparatus comprising a carrier for the lasted shoe upper mounted for reciprocatory movement between a loading station and a pressing station, pressing means movable toward and away from said pressing station into and out of engagement with a lasted shoe upper at said pressing station, and actuating means responsive to movement of said carrier to said pressing station for actuating said pressing means, said pressing means comprising a pressing head, fluid operated means mounting said pressing head for movement toward and away from said pressing station and adapted for connection to a source of fluid under pressure for moving said pressing head toward said pressing station, resilient means urging said pressing head away from said pressing station, and control means for controlling in timed sequence the admission to and release from said fluid operated means of fluid from said source responsive to movement of said carrier to said pressing station.

4. Apparatus for pressing the bottom heel region of a lasted shoe upper, said apparatus comprising a carrier for the lasted shoe upper mounted for reciprocatory

movement between a loading station and a pressing station, pressing means movable toward and away from said pressing station into and out of pressing engagement with a lasted shoe upper at said pressing station, actuating means responsive to movement of said carrier to said pressing station for actuating said pressing means, said carrier comprising a slide mounted for generally horizontal reciprocation between said loading and pressing stations, resilient means urging said slide toward said loading station, stop means engageable with said slide to limit movement of the latter to said loading station, an upstanding pin on said slide removably engageable in a lasted shoe upper supported on the upper side of said slide to retain the lasted shoe upper in position on said slide, and retarding means engageable with said slide to retard its movement toward said loading station.

5. Apparatus according to claim 4, said retarding means comprising a leaf spring extending into a path of slide movement as it approaches said loading station for frictional retarding engagement with said slide.

6. Apparatus for pressing the bottom heel region of a lasted shoe upper, said apparatus comprising a base, a carrier mounted on said base for generally horizontal reciprocatory movement between a loading station and a pressing station and adapted to carry an inverted lasted shoe upper, a pressing head mounted over said pressing station for generally vertical movement into and out of pressing engagement with a lasted shoe upper at said pressing station, and actuating means responsive to movement of said carrier to said pressing station for actuating said pressing head, said pressing head comprising a mounting member movable vertically toward and away from said pressing station, a pressing member interposed between said mounting member and said pressing station, a stiff coil spring interposed between and having its opposite ends fixed to said mounting member and pressing member to connect the latter to said mounting member for resiliently yieldable universal movement relative thereto, and a rigid pin on one of said mounting and pressing members projecting loosely into the other of said mounting and pressing members for limiting movement of said pressing member relative to said mounting member.
